UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY. A CORPORATION OF NEW JERSEY.

INSOLE-LIP-SEWING MACHINE.

1,089,473.

Specification of Letters Patent. Patented Mar. 10, 1914.

Application filed January 14, 1910. Serial No. 538,087.

To all whom it may concern:

Be it known that I, ALBERT E. JOHNSON, a citizen of the United States, residing at Beverly, in the county of Essex and State 5 of Massachusetts, have invented certain new and useful Improvements in Insole-Lip Sewing Machines; and I do hereby declare the following to be a full, clear, and exact description of the invention, such as will enable others skilled in the art to which it 10 pertains to make and use the same.

This invention relates to sewing machines for forming insoles, and more particularly to sewing machines for forming what are 15 known commercially as "Economy" insoles.

In forming the Economy type of insole the blank is treated by slitting its face to form a channel and by slitting the edge to 20 form a feather, these operations producing two independent, contiguous flaps at the margin of the blank. The two flaps thus formed are turned up from the channel and the feather and secured together to form a 25 single, compound lip. Thereafter reinforcing fabric, such as canvas, is applied to the face of the insole and to the lip.

The present invention contemplates an improvement in the formation of insoles of the 30 general character described and relates particularly to the step of bringing the channel and feather flaps together to form a single, compound lip. Heretofore the two flaps have been secured together either by cement 35 or by a line of stitches formed in the usual manner by means of well-known stitch forming mechanism in sewing machines suitably modified to adapt them to this particular class of work.

The object of the present invention is to 40 modify and adapt the domestic Willcox & Gibbs, or similar type of sewing machine, to sewing together the lips of Economy and other combination insoles.

In accordance with this object one feature 45 of the invention comprises a work supporting guide or positioning device adapted to bear on the grain side, or unchanneled surface, of the insole, so constructed and arranged that when the insole is presented to the machine with one of its flaps resting on a work table shaped to accommodate it, the two upturned flaps will be held, throughout the operation, in such relation to the stitch

forming mechanism as to properly receive 55 the stitches. The guide is preferably in the form of a roll to exclude friction and so mounted that the space above and in front of the work table is unobstructed, thereby permitting the insole readily to be inserted 60 and removed and providing for its free and easy manipulation during the stitching operation. The axis of rotation of the roll is oblique to the plane of the work table thereby permitting the insole to be flexed out- 65 wardly to clear the working parts above the work table during its feed through the machine. Means is provided to withdraw a guide, so mounted, from its engagement with the insole at the time the presser-foot 70 is lifted to further assist the operative in inserting the insole in working position and removing it therefrom. The preferred manner of accomplishing this end is by controlling the movement of the presser-foot and 75 guide from a single actuator. The feature of the invention just described is not to be understood as limited to use in a sewing machine of the Willcox & Gibbs type, as illustrated, as it is applicable to any sewing 80 machine adapted to secure together the flaps of insoles.

The necessary change in the size of the work table in order to properly accommodate and position the insole flaps places the 85 marginal portion of the insole, when in working position, somewhat in the path of the rotary thread hook or cast-off forming a part of the stitch-forming mechanism. A further feature of the invention consists in 90 the provision of a guard plate or cap inclosing the upper portion of the path of the thread hook thus effectively housing it and preventing its engaging and injuring the insole in the operation of the machine or in- 95 juring the hand of the operative.

In order to provide for an engagement of the feeding foot with the base of the lip of the insole, the foot is lightened to a considerable extent and arranged to operate at 100 the outer edge of the work table. In such a location there is liability of the feed foot engaging the edge of the insole, on the up-stroke of its four-motion feed, instead of the base of the flap unless means is provided to 105 insure a proper engagement of the feed foot with the work.

In accordance with a further feature of

- the invention a gage for the insole is provided in a plane outside of the plane of operation of the feed foot, which maintains the marginal portion of the insole always in front and out of the path of movement of the feed foot. This gage may conveniently be formed by extending the thread hook guard downward in a plane outside of the plane of operation of the feed foot.
- 10 In sewing machines of the type described as at present constructed, when the machine is running without work, which necessarily occurs for several revolutions of the driving shaft whenever work is removed, at each 15 revolution of the shaft, the feed foot will engage and lift the presser-foot arranged just above and in opposition thereto. Such an engagement is particularly injurious to the feed foot soon wearing it out and requiring its replacement. Also, in a machine designed to sew together the two flaps of insoles with the feed foot lightened to the extent necessary to cause it to act properly on the insole flap, its strength is considerably weakened and in addition to the excessive wear an injurious strain would be placed upon it were it permitted to engage and lift the presser-foot in the manner just described.
- 20 An important characteristic of the invention is found in the provision of a device to prevent contact of the feed foot with the presser-foot when the machine is running without work. Such a device may conveniently comprise a stop mounted on the presser-foot bar and arranged to be engaged by the feed foot bar and cause the presser-foot to be held out of contact with the rising feed foot, thereby effectually preventing any 25 engagement of the feed foot and presser-foot. The stop may be adjusted so that it will not interfere with a proper operation of the feed foot when work is in the machine. This feature of the invention is not limited 30 in the scope of its application to a sewing machine modified to sew the lips of insoles but in its broader aspect is applicable to any sewing machine of the general type described.
- 35 Other features of the invention relate to certain devices, combinations and arrangements of parts hereinafter described and claimed, which possess advantages of construction and operation that will be apparent to those skilled in the art.
- 40 The preferred embodiment of the invention is illustrated in the accompanying drawings, in which—
- Figure 1 is a front elevation of a Willcox & Gibbs household sewing machine, in which the novel features of the present invention have been embodied; Fig. 2 is a detail, in plan, of the work table and associated parts below the line 2—2, Fig. 1; Fig. 3 is an elevation of the parts shown in Fig. 2; Fig. 4
- is a detail, in section, of the feed foot and its bar taken on the line 4—4, Fig. 3; and Fig. 5 is a detail of the presser foot showing it in side elevation, bottom plan and transverse section on the line α — α .
- 50 In the embodiment of the invention illustrated in the drawings, the Willcox & Gibbs sewing machine there shown is provided with the usual stitch forming mechanism including a straight eye-pointed needle 2 and a rotary thread hook or cast-off 4. The thread hook is rotated by being mounted directly upon the driving shaft 6 and the needle bar is reciprocated, in guides on the frame, by the oscillations of a pivotally mounted lever 8 actuated from an eccentric on the driving shaft 6, all as usual. A four-motion feed foot 10 is carried by a feed bar 12 (see Fig. 4) which is pivoted at 14 to the machine frame and operated in the usual manner by a crank on the driving shaft which operates within a slot 16 at the free end of the feed bar. A presser-foot 18, to be described later, is carried by the usual presser-foot bar 20.
- 55 The machine as illustrated is provided with a thread pull-off comprising a thread pulling finger 22 actuated by a movement of a hooked rod 24, but as this mechanism does not form a part of the present invention, being claimed in a co-pending application of same date herewith, Serial No. 538,086, it need not be described in detail.
- 60 Instead of the usual large, flat work table provided with domestic sewing machines, in the present machine the work table 26 is made quite small, as shown in Fig. 2. It is removably held in a casting 25 with its outer edge (shown at the left and at the bottom in Fig. 2) in a plane but slightly at one side of the plane of operation of the needle 2. This change in the size and location of the work table is to permit it to support the two upturned flaps of an insole in such position relative to the stitch forming mechanism as properly to receive a line of stitches. When the insole is in working position its edge flap rests upon the work table, the outer edge of the work table extends well into the angle between the outer flap and the feather, and the channel flap is engaged by the presser foot 18. A portion of an insole in working position upon the work table is illustrated in Fig. 1. The necessary position of the work, in order to receive a line of stitches (see Fig. 1), leaves only a small portion of the surface of the work available upon which the feed foot may operate. To enable the feed foot to operate in the small area left for it, it is considerably lightened over the feed foot in ordinary use in domestic sewing machines. In its present form the feed foot comprises a thin blade (see Fig. 4) which is adapted to engage the base of the flap of the insole which rests upon

the work table, thereby permitting the stitching to take place near the upper edges of the flaps as is desirable for reasons well known to those skilled in the art.

5 The small area of the work table leaves the thread hook 4 exposed and, owing to the position of the insole in the machine, unless some protection be provided, the thread hook, in its rotation, is liable to injure either 10 the marginal portion of the sole by engagement therewith or the hand of the operative who directs the feed of the work through the machine. To prevent such injury the thread hook is provided with a cap or guard 15 28 (Fig. 3), removably supported in the casting 25, which incloses the upper portion of the path of movement of the thread hook, thus effectively housing it and preventing its coming in contact with either the work or 20 the operative. When the work is placed in the machine in the position shown in Fig. 1, the insole must be bent or flexed outwardly in order to clear the mechanism above the work table and this tends to throw the marginal portion of the insole, extending below 25 the work table, inward to a position where its edge would be engaged by the rising feed foot, thus interfering with the proper feed of the insole. To obviate this difficulty the 30 guard plate 28 over the thread hook is provided with a depending edge plate 30 arranged in a plane outside of the plane of operation of the feed foot (see Fig. 2). This plate provides a bearing for the feather of 35 the insole and forms a gage to hold the marginal portion of the insole out of the path of movement of the feed foot (see Fig. 1).

In order to maintain the two flaps of the insole in stitch receiving position during the 40 operation of the stitch forming mechanism, the machine is also provided with a work positioning device or guide comprising a roll 32 adapted to bear upon the unchanneled face of the insole at a point opposite the flaps. This roll is mounted upon one arm 34 of a bell-crank lever which is pivoted at 35 in a bearing located upon the machine frame at a point below the work table. This mounting of the work guide provides for an 45 unobstructed space above and in front of the work table, thereby permitting the insole readily to be inserted and removed and also provides for a free and easy manipulation of the insole by the operative during the 50 stitching operation. The guide roll 32 is held in working position by means of a coiled spring 37 suitably connected by its ends to pins upon the bell-crank lever arm 34 and the machine frame. The other arm 55 60 of the bell-crank lever which supports the work guide, is connected by means of the well known yoke and sliding block to the forwardly extending arm 38 of a second bell-crank lever pivoted at 39 in a bearing 65 formed on the casting 25. The rearwardly

extending arm 40 of this latter bell-crank lever has depending therefrom a chain 42 which is connected to any usual or convenient form of operating treadle (not shown). With this construction, when the treadle is moved in a direction to depress the bell-crank arm 40 motion is communicated from the bell-crank arm 38 to the bell-crank arm 36 in a direction to move the guide roll outwardly into a position to permit insertion or removal of the work. When the treadle is released, the spring 36 returns the guide roll to its working position. An adjustable stop 33 is provided to limit the inward movement of the bell-crank arm 34 when no work is in the machine so as to avoid injury to the operating mechanism by an engagement of the guide roll therewith.

As the presser foot 18 must be lifted before the work can readily be removed from the machine, means may conveniently be provided for lifting the presser-foot at the time the guide roll 32 is removed from working position. To this end a lever 44 is pivoted at 39 and is adjustably connected at its rear end in a well known manner (see Fig. 1) to the bell-crank arm 40, its forward end extending to a position beneath a shoulder 46 (see dotted lines Fig. 1) formed on the presser-foot rod. The lever 44 is preliminarily adjusted to a position to allow for changes in the position of the guide roll, due to the varying thickness of the work as it is fed through the machine without an engagement of the lever 44 with the shoulder 46. The space provided for this purpose, however, though sufficient to prevent an impulsive lifting of the presser-foot, is not sufficient to prevent the proper operation of the lever 44 when the bell-crank arm 40 is depressed by means of the treadle.

In order that the machine may operate upon the flaps of insoles having quite sharp toes, the presser-foot 18 is given a curvature upon a small radius, in practice about $3/16''$, and its extremity is beveled at its inner side toward the tip of the foot. The underside of the end of the foot is also beveled toward its inner edge, for a purpose presently to be explained, so as to leave an extension or rib 48 (see Fig. 5) at its outer edge. This rib serves two purposes.

It frequently happens that the flaps, and particularly the channel flap, fall back toward the sole from the position attained after the setting operation. The usual flat presser-foot cannot readily obtain a good bearing on a flap in this condition and has a tendency to slip off the flap and onto the work table. Under these conditions there is a constant tendency for the sole to be forced outward, against the pressure of the guide roll, and off of the work table. With the under side of the presser foot beveled as described, an angular entrant edge is pre-

sented to the work which permits the foot readily to enter the channel, complete the setting of the flap and place it in proper position to receive the stitches. In turning a sharp toe the pointed end of the foot acts to engage the flap, at the advance side of the toe, below its edge and within the channel before the turn is made. The end of the foot thereafter acts as a wedge to force an 10 improperly set flap outward away from the sole. The rib 48 is at the same time placed in the channel and acts on the flap as a retainer to prevent the foot at this time from slipping off of the channel flap and onto the 15 work table. The rib 48, also, fits well into the shoulder formed at the base of the channel flap and by means of the grip thus obtained assists in guiding the insole into stitch receiving position. To accomplish 20 the same purpose the gage plate 30 is provided at its upper edge, at a point substantially opposite the presser-foot, with a similar rib 50 (Figs. 2 and 3) which engages the shoulder at the base of the feather. The 25 guide roll 32 and the ribs 48 and 50, just described, act together to maintain the insole in proper position during its feed through the machine to receive a line of 30 stitches through the two flaps.

30 The presser-foot bar 20 is provided at its lower end with a stop 52 (Figs. 2 and 3) having a collar surrounding the presser rod and held in any desired position of vertical adjustment by means of a clamp screw 53. 35 When no work is in the machine the feed bar 12, as it rises during its four-motion movement, will engage the stop 52 before the feed foot 10 engages the presser-foot 18 and the presser-foot will, therefore, be held 40 out of contact with the rising feed foot. The adjustment of the stop 52 upon the presser-foot bar is such that while the feed foot is prevented from engaging the presser-foot when the machine is running without 45 work, it nevertheless does not prevent a proper feeding engagement of the feed foot with the work when work is passing through the machine. If the feed foot 10, which, as explained, is quite delicate, were permitted 50 to engage and lift the presser-foot, as is customary, it would be liable to injury. The stop 52 effectually prevents injury to the feed foot from this cause.

The stitching of the upturned flaps starts 55 at one shank and the insole is fed through the machine automatically, being guided by the operative until the other shank is reached when the guide-roll and presser-foot are withdrawn and the insole removed from 60 the machine. With the construction described, the flaps are immediately and positively secured together by a line of stitches properly located relatively to the base of the flaps and insuring a retention of both the 65 flaps in upturned position while the rein-

forcing fabric is being applied and during the stitching of the upper and welt to the insole.

In the following claims the term "feather" is descriptive of that portion of the margin of the insole lying beneath the outer one of the two flaps which are cut from the substance of the insole, however the insole is slit or cut to produce such flap.

The nature and scope of the present invention having been indicated and the preferred embodiment of the invention having been specifically described, what is claimed as new is:—

1. A sewing machine for securing together the two contiguous flaps of an insole having a channel and a feather, having, in combination, stitch forming mechanism, a work table adapted to engage the outer flap and having its outer edge extending into the angle between the outer flaps and the feather, a presser-foot adapted to engage the channel flap, a work guide to bear on the unchanneled face of the insole and hold the flaps in stitch receiving position on the work table, and a support for the guide rising from the machine frame below the work table.

2. A sewing machine for securing together the two contiguous flaps of an insole having a channel and a feather, having, in combination, stitch forming mechanism, a work table adapted to engage the outer flap and having its outer edge extending into the angle between the outer flap and the feather, a presser-foot adapted to engage the channel flap, a work guide obliquely arranged with respect to the surface of the work table to bear on the unchanneled face of the insole and hold the flaps in stitch receiving position on the work table, and a support for the guide rising from the machine frame below the work table.

3. A sewing machine for securing together the two contiguous flaps of an insole having a channel and a feather, having, in combination, stitch forming mechanism, a work table adapted to engage the outer flap and having its outer edge extending into the angle between the outer flap and the feather, a presser-foot adapted to engage the channel flap, a work guide to bear on the unchanneled face of the insole and hold the flaps in stitch receiving position on the work table, a movable support for the work guide arranged below the work table, a spring to hold the guide in working position, and means under control of the operative to move the guide out of working position.

4. A sewing machine for securing together the two contiguous flaps of an insole having a channel and a feather, having, in combination, stitch forming mechanism, a work table adapted to engage the outer flap and having its outer edge extending into the

- angle between the outer flap and the feather, a presser-foot adapted to engage the channel flap, a work guide to bear on the unchanneled face of the insole and hold the 5 flaps in stitch receiving position on the work table, a movable support for the work guide fulcrumed at a point below the work table, a spring to hold the guide in working position, and means under control of the operation 10 to simultaneously lift the presser-foot and remove the guide from working position.
5. A sewing machine for securing together the two contiguous flaps of an insole, having, 15 in combination, stitch forming mechanism, a work table, a feed foot operating in front of the outer edge of the work table, and a work gage arranged in a plane outside of the plane of operation of the feed foot to 20 maintain the marginal portion of the insole out of the path of movement of the feed foot.
6. A sewing machine for securing together the two contiguous flaps of an insole, having, 25 in combination, a work table adapted to engage one of the flaps, stitch forming mechanism including a rotary thread hook adjacent the work table, a feed foot operating in front of the outer edge of the work 30 table, and a plate extending over the top and depending over the outer face of the thread hook, said depending portion lying in a plane outside of the path of movement of the feed foot, to protect the marginal portion 35 of the insole during the stitching operation.
7. A sewing machine for securing together the two contiguous flaps of an insole, having, in combination, stitch forming mechanism, 40 a presser foot continually in engagement with the work, a feed foot arranged and acting to press the work against the presser foot to grip and feed the work, and a stop mounted on the presser-foot bar adapted 45 when no work is in the machine to be engaged by the feed foot bar before the feed foot reaches a position to engage the presser-foot.
8. A sewing machine for securing together 50 the two contiguous flaps of an insole, having, in combination, stitch forming mechanism, a work table to engage the outer flap, and a presser-foot to engage the channel flap having its extremity beveled at its 55 inner side toward the tip of the foot forming an entrant wedge to open the channel in advance of the foot and its underside beveled toward its inner edge.
9. A sewing machine for securing together 60 the two contiguous flaps of an insole, having, in combination, stitch forming mechanism, a work table to engage the outer flap, and a presser-foot to engage the channel flap having its extremity beveled at its 65 inner side toward the tip of the foot forming an entrant wedge to open the channel in advance of the foot and its underside beveled toward its inner edge.
10. A sewing machine for securing together 70 the two contiguous flaps of an insole, having, in combination, stitch forming mechanism, a work table adapted to engage one of the flaps, and a curved presser-foot to engage the other flap provided with a channel shoulder engaging rib at its outer edge to assist in guiding the insole into 75 stitch receiving position.
11. A sewing machine for securing together 80 the two contiguous flaps of an insole, having, in combination, stitch forming mechanism, a work table adapted to engage one of the flaps, a presser-foot to engage the other flap, a rib at the outer edge of the presser foot and a rib coöperating therewith to engage the insole material at the base of 85 the flaps and assist in guiding the insole into stitch receiving position.
12. A sewing machine for securing together 90 the two contiguous flaps of an insole having a channel and a feather, having, in combination, stitch forming mechanism, a work table for supporting the insole by engaging the outer flap and having its outer edge extending into the angle between the outer flap and the feather, an upwardly extending bell-crank lever fulcrumed below the work table having a guide roll on one arm to bear on the unchanneled face of the insole and hold the flaps in 95 stitch receiving position on the work table, a second bell-crank lever having one arm operatively connected to the second arm of the first lever, and operating means connected to the free arm of the second lever for moving the guide relatively to the work. 100
13. A sewing machine for securing together 105 the two contiguous flaps of an insole having a channel and a feather, having, in combination, stitch forming mechanism, a work support for supporting the insole by engaging the outer flap and having its outer edge extending into the angle between the outer flap and the feather, a pivotally mounted work guide to bear on the unchanneled face of the insole and hold the flaps in 110 stitch receiving position on the work support, a lever for actuating said work guide to move it relatively to the work, a presser-foot, and means connected to said actuating lever for lifting the presser-foot at the time 115 the guide is moved.
14. A sewing machine for securing together 120 the two contiguous flaps of an insole having a channel and a feather, having, in combination, stitch forming mechanism, a work support for supporting the insole by engaging the outer flap and having its outer edge extending into the angle between the outer flap and feather, a pivotally mounted work guide to bear on the unchanneled face 125

of the insole and hold the flaps in stitch receiving position on the work support, a lever for actuating said work guide to move it relatively to the work, a presser-foot, a presser-foot lifting lever connected to said actuating lever for lifting the presser-foot at the time the guide is moved, and means permitting adjustment of said lifting lever

to a position to prevent movement of the presser-foot during slight movements of the 10 guide.
